UNITED STATES PATENT OFFICE.

BRADLEY A. FISKE, OF THE UNITED STATES NAVY.

METHOD OF POINTING GUNS AT SEA.

SPECIFICATION forming part of Letters Patent No. 435,925, dated September 9, 1890.

Application filed May 15, 1890. Serial No. 351,857. (No model.)

To all whom it may concern:

Be it known that I, BRADLEY A. FISKE, of the United States Navy, have invented a new and useful Method of Pointing Guns at Sea, 5 of which the following is a specification.

My invention relates to a new method of pointing guns located upon a vibrating, heeling, or rolling platform—such as a ship—upon a distant target; and it consists (after 10 determining the angle of elevation above the horizontal which it is necessary to give the gun in order to cause the projectile to traverse the given range) in adjusting a telescope movable about a transverse axis approxi- 15 mately parallel to that of the gun at an angle to the axis of the bore of said gun equal to said predetermined angle of elevation, and then noting the moment when the line of sight of said telescope so adjusted intersects the 20 target.

In the accompanying drawings, Figure 1 illustrates a vessel on an even keel, showing the vessel's deck, the gun, and the telescope all horizontal and parallel. Fig. 2 shows the 25 vessel heeled over a determinate angle, the gun still remaining parallel to the deck, but the telescope disposed with reference to the deck over an angle equal to that of the heel of the vessel. Fig. 3 shows the vessel heeled over a determinate angle less than that shown in Fig. 2, the gun being elevated above the deck through the remaining part of that angle and the telescope depressed over an angle equal to the heel of the vessel.

Similar letters of reference indicate like 35 parts.

A represents a section of the hull of a ves- sel, B C the water-line, and D E the line of the deck.

F is a gun mounted on the deck and cap- 40 able of being elevated or depressed, turning on its trunnions G.

H is a telescope or spy-glass supported on transverse pivots or trunnions in any suit- 45 able way above the deck, and also capable of being turned on vertical pivots so as to point at any object.

In Fig. 1 the vessel A is shown on an even keel, the deck-line D E, axis of the gun F, 50 and axis of the spy-glass H all being parallel and horizontal.

Let it be assumed that the gun is to fire at a target located at such a distance from the ship that the necessary elevation to be given to the gun above the horizontal would be (to 55 illustrate) two degrees; but suppose the ship heels over, as indicated in Fig. 2, so that the deck-line makes an angle E I C equal to two degrees. Then, clearly, the axis of the gun being parallel to the deck will make an angle 60 of two degrees with the horizontal, and thus by the rolling or heeling of the ship the gun will be brought to the desired elevation. If it be then fired, its projectile will (as assumed) traverse the distance to the target. The ob- 65 ject of the telescope H is to determine the moment when the vessel in rolling or heeling reaches the point at which the gun attains the desired elevation. To this end, as soon as the extent of elevation is determined, the 70 telescope is set so that the angle between its axis and the axis of the gun shall equal this angle—that is, assuming, as before, the angle of elevation of the gun to be two degrees, the object end of the telescope is depressed two 75 degrees. (Full lines, Fig. 2.) Therefore the angle between the line of sight of the tele- 80 scope and the axis of the bore of the gun will be two degrees. The observer now looks through the telescope until he sees the cross- 85 hairs of the telescope intersect the target, which may be assumed in all cases, without material error, to be located in a level line drawn from the telescope. In order that the cross-hairs may intersect the target the ves- 90 sel must heel or roll, so as to bring the tele- scope back to the horizontal, or in the pos- 95 sition indicated by the dotted lines, Fig. 2. When this happens, the gun is in the position shown, and hence at the desired elevation. Suppose, however, that by reason of the smoothness of the sea the vessel does not roll or heel sufficiently to elevate the gun to the desired extent. Assuming this, as before, to be two degrees, let one degree be the maximum elevation producible by the heeling of the vessel. These conditions are illustrated in Fig. 3, the angle between the deck-line D E and the water-line B C being one degree. The gun is then elevated on its trunnions 100 over an angle of one degree, and inasmuch as the angle between gun and telescope must

equal that of the desired elevation of gun, the telescope is depressed one degree, so that the angle between gun and telescope, as before, becomes two degrees. Therefore, when 5 the telescope is brought level by the heeling of the ship and the target sighted through it the gun will stand at an elevation of two degrees above the horizontal—one degree being obtained by the heeling of the vessel and one 10 degree by the gun's own elevation on its trunnions G. Of course the gun may be laid at any angle of elevation and the telescope adjusted conformably.

The assumption made in the foregoing, that 15 the line from the telescope to the target floating on the water is a horizontal line, is strictly true only when the telescope points at a part of said target which is at the same height above the water as the telescope itself; but 20 under ordinary conditions of practice this refinement may be neglected and the gun fired when the cross-hairs of the telescope cut any part of the target.

Among the advantages gained by my afore- 25 said method are that it does away with the use of all mechanical contrivances—such as pendulums, spirit-levels, &c.—and allows the gun to be accurately adjusted in elevation with reference simply to the true horizontal 30 line. It renders unnecessary frequent ad-

justment of the gun itself on its trunnions to effect changes in elevation, the telescope being correspondingly depressed instead. It places the determination of the instant of firing the gun in the control of a person distant 35 therefrom, and hence in a position away from the excitement and hurry prevailing in the immediate vicinity of the gun; and finally, the piece can be sighted much more accurately by means of the telescope than is possible 40 by the use of the rough sights on the gun itself.

I claim—

The method of pointing a gun located on a rolling, heeling, or vibrating platform, which 45 consists in adjusting a telescope, also located on said platform and movable on a transverse axis approximately parallel to that of the gun, at an angle to the axis of the bore of the said gun equal to a certain predetermined angle 50 of elevation necessary to cause the projectile fired from said gun to travel to a given target, and, second, noting the moment when the line of sight of said adjusted telescope is caused by the movement of said supporting-platform 55 to intersect said target.

BRADLEY A. FISKE.
